UNITED STATES PATENT OFFICE.

FRANK WILLIAM KENT, OF STREATHAM HILL, LONDON, ENGLAND.

PHOTOGRAPHIC TRANSFER PROCESS.

No Drawing.

Application filed December 6, 1921. Serial No. 520,243.

To all whom it may concern:

Be it known that I, FRANK WILLIAM KENT, a subject of the King of Great Britain, residing at 5 Thornton Avenue, Streatham 5 Hill, in the county of London, England, have invented certain new and useful Improvements in or Relating to Photographic Transfer Processes, of which the following is a specification.

10 This invention relates to photographic transfer processes and has for its chief object to secure a more effective and natural rendering of the subject, intensifying the shadows and throwing up the high lights 15 in a more efficient manner than has heretofore been obtained in ordinary or transfer photographic work.

According to this invention the transferred print, having a matt or nearly matt 20 surface, is provided with an underlayer or substratum of a reflecting or shiny character lying between the film and the paper, card or other mount. The substratum may be produced by the aid of a gelatine adhesive 25 layer so prepared as to give a sheen showing through the transferred emulsion. The effect of this shiny under surface is to increase the reflection of light through the parts of the print which are not too dense and especially through the parts which represent 30 high lights, with the result that the lighter parts of the print are thrown into much greater relief than is the case with ordinary photographs, while the dark portions or 35 shadows are intensified, giving an effect which much more closely approaches the natural appearance of objects than is obtained by any of the usual photographic methods. In the complete print there are

40 three surfaces of reflection, the upper surface, where the reflection is reduced by the matt effect, the paper or other mount, and the surface of contact or union between the back of the transferred film and the underlayer, which reflecting surface lies between the first two. The increase of reflecting 45 power at this intervening surface in accordance with the present invention gives the enhanced effect sought.

50 A convenient method which may be adopted in carrying out this invention is to coat the paper, card or other mounting material with a solution of gelatine, a suitable strength being about 2½ per cent or more of gelatine dissolved in hot water, applying the solution rapidly to the mount over a

sufficiently large area to take the print and as evenly as possible, leaving considerably more gelatine than is required to make the photograph adhere. The card or paper 60 mount is preferably previously damped or soaked for about a minute or until it becomes limp, in cold water, laid on a flat surface and the surplus water removed with a sponge whereupon the gelatine is applied, 65 and the print is also damped or soaked and has its surplus water sponged from it. The print may be prepared with a stripping substratum in accordance with the specification of my prior Application No. 443412 but the 70 present process is not confined to any special type of transfer print excepting that it must have matt or nearly matt shadows after transfer, and be of such a nature that the light can readily pass through it and be reflected by the backing, to give the required 75 effect.

80 In preparing the transfer print in accordance with the method referred to, a hardening agent such as alum, or more especially chrome alum, is applied to the base to which the emulsion is applied, a solution of the hardening agent, together usually with an anti-greasing agent, such as quillaia bark, is spread on the base, which may be a waxed paper base, and is allowed to dry. The hardening agent, must, of course, be free of any gelatine or other material which will allow it to become effective, and, therefore, use up its hardening properties. The 85 sensitive emulsion is then spread over the dried substratum and the hardening agent becomes active at the under-surface of the film so that the film is strengthened and upon transfer the backing can be readily 90 stripped off in the usual manner.

95 The damp print is then placed face down on the mount, upon the coating of gelatine, the print being lowered gently down from one edge on to the gelatine surface, any air 100 bubbles and surplus gelatine being squeezed out in the process of laying down and the surplus gelatine removed with a gelatine brush, or a sponge. The mount surrounding the print is then sponged with clean water to 105 remove any traces of gelatine.

Drying is effected by placing the mounted print in a current of warm air so that it 110 dries fairly quickly; when dry the original support of the film being pulled away from the mount, leaving the picture on the mount with a shiny layer of gelatine beneath the

film. The excess gelatine which is put on the mount is to minimize the risk of air bubbles getting in between the film and the mount and avoids the necessity for heavily 5 squeezing the transferred film, the method adopted giving a very even layer of gelatine.

In cold weather the damp mount may be laid on a warm surface such as a folded piece 10 of fabric quickly removed from a dish of hot water or the wet fabric may be laid on a warm surface such as glass, this keeping the mount sufficiently warm to prevent the gelatine from setting before the transfer is 15 complete. When the print has been laid down the mount can be removed to a cold surface such as a sheet of cold glass, quickly chilling the gelatine and allowing of sponging the mount without shifting the print.

20 The actual method of mounting can of course be varied, and a very satisfactory method in cold weather is to lay the damp mounting paper or card upon a piece of glass a little smaller than the card and just removed from warm or hot water before applying the gelatine; a soft gelatine is preferably employed, which may be put on with a brush or poured on the mount from a spouted jug, the warm glass providing sufficient heat to prevent the gelatine setting before the print is in position; the surplus gelatine can be poured into a jar and the margins of mount sponged with clean water to remove the traces of gelatine, after 25 which the mounted print is removed from the glass and dried. By this method no gelatine is likely to get on the back of the mount. The best temperature of gelatine solution and water for warming the mounting glasses or fabric depends on the atmospheric temperature, as also does the temperature of the gelatine solution for mounting, such temperatures being readily determined by a little experience, as all that is required is enough heat to keep the gelatine solution in a sufficiently liquid condition till the print is properly laid down on the mount. Any other method of mounting 40 which produces the underlying shiny layer may, however, be employed in the process, preference being given to a transparent adhesive.

The strength of gelatine solution can also 55 be varied; generally from $2\frac{1}{2}$ per cent to 5 per cent will be satisfactory; the warmer the weather the stronger the solution. For wood, glass, and such like surfaces a 5 per cent solution will generally be found satisfactory.

60 No added pressure is put upon the print after it is laid upon the mount, merely the weight of the wet print being utilized; squeegeeing would squeeze out some of the 65 gelatine and spoil the effect.

Most ordinary photographs on paper or card show a gloss or sheen more or less over the whole surface in the case of certain papers however, it has been found possible to eliminate the gloss and produce a matt or 70 nearly matt surface without a glossy effect, but the result of this is often a loss of brilliancy. On the other hand engravings on 75 vellum or a similar surface appear much more brilliant than ordinary photographic prints owing to the contrast produced between the uninked surface and the matt or nearly matt surface of the ink, by the sheen of the vellum. The present process obtains an effect by purely photographic means 80 which approaches that of an engraving printed on vellum or a similar surface.

The photographic transfer print may be prepared in accordance with the method described in my specification No. 443,412 already mentioned but any suitable method of preparing the matt or nearly matt transfer print may be employed. The method employed must not impair the ability of the film to transmit light readily through the parts which are not in deep shadow. In a common method of transferring, a gelatine solution is brushed over the face side of the wet print and the print is then laid down on its final support and squeezed into contact with the mount surface and then allowed to dry but it is somewhat difficult by this method to obtain the even, shiny underlying surface which is required according to the present invention, where if a gelatine layer is used as already described it is applied in considerable excess to the surface of the mount, and no added pressure or squeegeeing is necessary.

What I claim and desire to secure by Letters Patent of the United States is:—

1. A process for the production of a photographic transfer print which consists in coating the mount with a liquid which when dry possesses a reflecting or shiny surface and in laying a transfer print having a substantially matt surface upon the said liquid and causing it to adhere without the application of pressure, for the purpose specified.

2. A process for the production of a photographic transfer print which consists in coating the mount with a gelatine solution forming a layer of substantial thickness and in laying a transfer print having a substantially matt surface upon the said gelatine solution before drying and causing it to adhere without the application of pressure, for the purpose specified.

3. In a process as claimed in claim 2, damping the transfer mount, laying it upon a warm surface before transferring the print and cooling the mount after transferring.

FRANK WILLIAM KENT.
